UNITED STATES PATENT OFFICE

LUCIAN F. EASTON, OF LA CROSSE, WISCONSIN

ROTARY AIR PUMP

Application filed September 3, 1929. Serial No. 390,158.

This invention relates to a rotary air pump of the type which employs a rotor operating in a body of water which by centrifugal action is driven to the periphery of the casing 5 and serves to trap a charge of air between each pair of rotor blades, which is thereafter expelled by the inward propulsion of the water due to a contraction in the peripheral wall of the casing.

10 The object of the present invention is to improve the construction and arrangement of the rotor and the method of sealing the same by a water seal; and the invention relates to the means provided for admitting water to 15 the interior of the rotor chamber, and to the configuration of the rotor blades and the wall of the casing.

The invention further relates to means provided for disabling the pump by the escape 20 of water from the rotor chamber when it is desired to rotate the pump idly; and further to the means provided for insuring the return of water to the rotor chamber to cause a resumption of pumping operations.

25 These results are attained by the utilization of differential pressures within the rotor chamber and the outer casing respectively, and the pump is especially designed to utilize such differentials in a manner presently to be pointed out in detail.

The invention also relates to the general construction of the pump as a whole and the individual parts and elements thereof.

In the drawings:

30 Figure 1 is a longitudinal sectional elevation of the pump in one of its forms, indicating a range of water levels which may be advantageously maintained in the outer chamber;

Fig. 2 is a cross sectional elevation taken on line 2 of Fig. 1;

Fig. 3 is a longitudinal sectional elevation of a modified arrangement of the pump, showing the water outlet and inlet ports different- 45 ly located; and

Fig. 4 is a detail showing devices for automatically controlling the means for disabling the pump.

The pump, as shown in Figures 1 and 2, 50 comprises a boxlike casing which is com-

posed of a main or body section 10 having a base 11, side walls 12, end walls 13, and a top wall 14. As shown, this main or body section of the casing is integrally formed, although it might be otherwise constructed if so de- 55

Within the center of the body section, and extending between the side walls 12 thereof, is located a cylindrical outer cross wall 15 surrounding a cylindrical inner cross wall 60 15^a, which circumscribes a rotor chamber 16, the sides of which are provided by circular plates 17, which constitute in effect continuations of the side walls 12, and serve to clamp the inner cylindrical wall 15^a in place. This 65 gives to the inner section of the pump a drum-shaped formation with a double cylindrical wall and flat sides.

Integrally formed with the outer cross wall 15 is an air inlet passage 18 into which is entered an inlet pipe 19 which leads from the heating system or other device or apparatus from which it is desired to exhaust the air, and which may be controlled by a check valve 20 presently to be described. 70 75

The upper portion of the air inlet passage extends vertically, but the lower portion extends obliquely, with the walls converging from circular to oblong cross section to the point where the passage which continues 80 through the cylindrical cross wall 15^a enters the rotor chamber, one of the walls 21 of the passage being extended inwardly beyond the other.

The wall 21 constitutes a terminus of a 85 thickened portion of the inner cylindrical wall 15^a, and this thickened portion constitutes a block-off wall 22, the inner configuration of which is such as to afford a somewhat abrupt inward convergence from the normal curvature of the inner wall 15^a to a curving surface 23, which is substantially coincident with the periphery of the rotor to allow a close clearance of the rotor blades. 90 95

Although, as shown in Figures 1 and 2, 95 the air inlet enters the rotor chamber at a point near the top, and although the block-off wall is correspondingly located with respect to the aforesaid arrangement of the inlet passage, it will be understood that the 100

particular arrangement shown in Figures 1 and 2 may be modified in various ways without departing from the spirit of the invention. Fig. 3 presently to be described shows one of such possible modifications.

5 At the point where the wall 21 of the inlet passage intersects the curved surface 23 of the block-off wall, a knife edge 24 is formed, and it is at this point that the water ring confined by the block-off wall 22 will be suddenly released from confinement and driven outwardly against the cylindrical wall 15^a.

10 Within the rotor chamber thus configured is located a rotor 25 mounted upon a shaft 26. The rotor comprises a hub 27 from which extend a plurality of arcuately formed blades 28, all of which, in the arrangement shown in Fig. 1, curve forwardly or in a clockwise direction, which is the direction of rotation 15 of the rotor in the form exemplified in Fig. 1.

15 The blades 28 are connected throughout their centers by the provision of a ring shaped web 29, the outer edge 30 of which is coincident with the tips of the blades, although, if desired, the blades or blade portions on 20 opposite side of the web might be given a staggered arrangement without departing from the spirit of the invention.

25 The inner edge of the ring-shaped web merges into the hub, thus dividing the rotor into two sections or divisions, constituting in effect two pumps mounted on a single shaft, although it is not deemed essential in all cases that the web extend inwardly to the point 30 of actual mergence with the hub, since the side sections or divisions of the rotor might in some circumstances be in communication through openings inside or through the web, as the case may be.

35 Each of the blades, along each of its side edges, is provided with a groove or channel 32 which leads outwardly from the hub to the top of the blade, and it will be noted from Fig. 2 that between the side walls 12 and the rotor a very slight clearance at all points 40 may be afforded, the actual amount of the clearance being exaggerated in the drawings for purposes of illustration. This clearance will be approximately .003 of an inch exclusive 45 of the depth of the grooves 32 which arrangement may permit a small amount of water to work through the grooves and through the clearance, which will assist in sealing these surfaces against the escape of 50 air along the edge of the rotor.

55 The side plates 17 at points adjacent to the hub of the rotor are provided with apertures 33, so that water admitted at these points will strike against the end of the hub, and by centrifugal action will be driven outwardly through the grooves 32, and to some extent through the clearance afforded between the rotor and the side walls 17.

60 The main or body portion of the casing, on each side thereof, is enclosed by a drum-

shaped casting, comprising a circular side plate 34 having a circumferential flange 35 which is inturned to afford a ring-shaped marginal wall 36 which abuts against and is secured to the wall 12 by means of through bolts 37, or in any other suitable manner. This arrangement furnishes outer side chambers 38 which communicate with the body chamber through upper and lower elongated ports 39 and 40.

65 The top wall 14 of the body of the casing is apertured to receive an air discharge pipe 41, which may lead to the atmosphere or elsewhere as desired. The body portion of the casing is provided with upper plugs 42 and lower plugs 43, which afford convenient access to the interior.

70 The shaft 26 is journaled through bushings 44 and 45, which are held in place within annular bosses 46 inwardly extending from the outer side plates 34. The air entrapped within the rotor pockets is driven out through discharge ports 47 in the side plates 17 in the rotor chamber at points inwardly adjacent to the beginning of the block-off wall 22, and, as shown in the construction in Fig. 2, below the axis of the rotor, although the relative position of these portions of the apparatus may be modified, as, for instance, in the construction shown in Fig. 3. The air thus discharged enters the outer side chambers 38 and is thence educted through the ports 39, and ultimately discharged through the outlet pipe 41.

75 For simplicity, the drawings show the side plates 17 secured by a press fit within the ring-shaped marginal walls 36, but of course any other means, such as screws or spring, may be used.

80 From experimentation it appears that the partial vacuum within the rotor chamber gradually diminishes from the inlet point to the discharge at the block-off, and this vacuum condition tends to more or less balance the centrifugal force.

85 Assuming that the outlet from the outer chamber is adequate, atmospheric pressure will practically at all times obtain here, being only slightly increased by the back pressure of the discharging air. It therefore follows that during active operation of the pump, with the inlet port 18 in communication with the return line of a vacuum system, or other apparatus from which the free admission of atmospheric air is normally excluded, a lower pressure will obtain within the rotor chamber particularly near to the inlet port where the vacuum creating action is greatest. From this it results that whenever the pump operates there will be a tendency of the water in the outer chamber to pass into the rotor chamber through all openings and clearances except where actually opposed by out discharging air. This tendency will, of course, be greater the higher 90

the vacuum condition, and under certain predetermined conditions will be sufficient to maintain an adequate supply of water for operating the pump.

The high and low water lines shown in Figures 1 and 3 merely indicate a close approximation of limiting levels to be maintained in the outer chamber, in order that there may be an adequate supply for operating the pump, and on the other hand not too much to cause an overloading of the motor driving the pump. These levels will change by flow from or to rotor chamber.

In order to provide a duct for the inflow of the water, the outer wall 15 of the rotor chamber is provided at its lowermost point with a plug 48 having in it a duct 49 which establishes communication with an annular groove or channel 50 which is formed between the circumferential walls 15 and 15^a respectively, and which communicates with the inlet duct 18. A different arrangement of these features is shown in Fig. 3, which will be presently described.

When differential pressure conditions are established, the water will be admitted to the rotor chamber through the duct and through the channel above described, so as to maintain a sufficient quantity of water in the rotor chamber to cause the pump to effectively operate.

A water outlet plug 51 is entered through the side wall of the rotor chamber, and provided with a duct 52, which is of proper dimensions to restrict the discharge of water from the chamber so long as there is an excess of pressure in the outer chamber as compared with the pressure maintained in the rotor chamber, but when communication with the atmosphere is established, the water is thrown out by centrifugal force, and with the large volume of air admitted to take its place is soon all expelled, and as the vacuum is reduced, less water is drawn in through the duct 49 and the channel 50.

The pipe 19 is shown as provided with a coupling 53, one branch of which connects with a pipe 54, which affords ingress for atmospheric air or gas. The admission of atmospheric air or gas may be regulated manually or automatically, but whenever such air or gas is admitted, it will tend to reduce the differential in pressure, that is, to establish equal pressure in the rotor chamber and in the outer chamber, so that under such conditions the action of the pump will be disabled so long as free communication with the atmosphere is maintained.

The check valve 20, if employed, is located in the return line from the vacuum or other system from which air is to be exhausted, and it comprises a casing 55, having at its lower end a valve seat 56 against which a valve 57 seats.

The valve 57 is provided with a valve stem

58 having at its upper end an adjusting nut 59 and a jamb nut 60, thus permitting regulation of the tension of a spring 61, which normally holds the valve seated. The provision of this check valve insures the maintenance of reduced pressure conditions within the rotor chamber so long as atmospheric air or gas is excluded, and at the same time permits the air or gas to be drawn past the check valve and withdrawn from the system during the normal operation of the pump.

The only advantage of employing the resistance in the valve 57 is when starting with an absence of vacuum conditions in the system. When, however, normal vacuum conditions have once been established, the resistance is no longer necessary, so that instead of a permanent resistance in the form of a spring, a hand operated resistance can be used until vacuum conditions are established in the system.

In Fig. 3 I have shown a modification which consists mainly in a re-positioning of the inner and outer walls of the rotor chamber with respect to one another. In this instance, the outer wall 15 stands as previously described, but the inner wall 15^a has been turned or rotated to reverse position of the block-off wall 220 and to bring the air inlet at the end 210 of the block-off wall to a point substantially at the base of the rotor chamber. The water inlet duct 49 is thus located in close proximity to the air inlet port, so that the water will more readily enter through the channel 50, which may constitute an advantage, in that it does not require the water to be lifted to the degree indicated in Fig. 2.

Also in Fig. 3 I have shown the water outlet duct 520 located at the top of the rotor chamber and formed in a pipe or tube 510 which extends through and above the casing and is threaded to receive an adjusting valve stem 511 operable by a handle 512, which permits regulation of the outflow of water through the duct 520, to the degree required to give maximum efficiency.

In this case, also, the side plates, numbered 170 in Fig. 3, have been shifted 180° to bring the air discharge port 470 to a higher point than previously indicated. This arrangement allows of a greater variation in the rise and fall of the water in the outer chamber, as indicated by the dotted high and low water lines, the low water line being located at the lowest level in the outer casing at which water will run into the rotor chamber, to resuscitate the pump after a period of disablement. The high water line is not intended to indicate the highest point at which the pump will operate, but an increase in the volume of water above that indicated will require somewhat more power to operate as more or less water will pass through the rotor chamber.

It will be noted that in Fig. 3 the discharge port 470 is located at the highest possible point, and that the water outlet port 520 is located in close proximity to the end of the block-off wall, which will result in a continual discharge of water through the port 470, even when high vacuum conditions are maintained.

However, it will be understood that the water outlet 52 (or 520 as the case may be) 10 may be located in any convenient location, so long as it is not so near the inlet as to afford an air leak into the rotor chamber. It will also be understood that although this outlet is shown in Fig. 3 as being manually controlled, it may be automatically controlled in a manner presently to be described.

The discharge of water from the rotor chamber is due in the main to centrifugal force which is more or less retarded in its 20 action by vacuum conditions in the rotor chamber. This retarding action, due to vacuum, will depend upon the location of the water outlet port 52 (or 520), the action of the vacuum being at a maximum near the air inlet and at a minimum near the outlet end of the block-off; where on the contrary the mechanical action of centrifugal force will be most effective due to the impingement of 30 the revolving water against the abrupt terminus of the block-off wall, so that these various factors effectively combine in the forcible ejection of entrapped air through the air discharge port, especially in the form of construction shown in Fig. 3.

With regard to the replacement of water which is drawn in by the suction of the pump, the size of the inlet 49 (or 490) can be such 40 that it will not easily stop up, but not so much that the water outlet will be unable to take care of the admitted water. For convenience and simplicity, the size of this inlet is fixed, although it might be controlled either automatically or otherwise.

The quantity of water drawn in will be greater the higher the vacuum, so that as the vacuum is reduced by the free admission of atmospheric air, the inflow of water will be reduced, thereby tending to disable the 50 pump, so that both the inlet and outlet from the rotor chamber will work together to the same end.

In Fig. 4 I have diagrammatically shown means for automatically regulating the adjustment of the valve stem which controls the water outlet port. In this instance the valve stem 513 which controls the port 520 is connected by a link 63 with a lever 64, the free end of which is balanced between bellows 65 and 66, the former of which connects by a pipe 67 with a portion of the system responsive to a water pump pressure, while the bellows 66 connects by a pipe 68 with a portion of the system responsive to the boiler pressure in a vacuum heating system, or it may be

a hydraulic head or other pressure in any pumping system. Lock nuts 62 provide an adjustable stop for limiting the movement of the valve stem to give maximum efficiency.

As the water pump pressure of pumping increases, the valve stem will be lifted to increase the discharge of water through the port 520, and thereby hasten the disabling of the pump while a decrease in the pumping pressure will cause a closing of the port 520 to restrict the discharge of water from the rotor chamber in the rehabilitating of the pump, in general accordance with the principles of operation defined in my co-pending application, Serial No. 371,200, filed June 15, 1929.

As shown, the bellows responsive to boiler pressure meets a condition sometimes present in vacuum heating where there may be vacuum in both pump and boiler, except that when the pump is running the vacuum will be less in the pump than in the boiler and water will pass from the pump to the boiler. In other words, the valve is seated by a fall in pump pressure and not by a rise in boiler pressure, or the valve may be said to be seated by excess of boiler pressure over pump pressure, and vice versa the valve is opened by an excess of pump pressure over boiler pressure.

Fig. 4 merely serves to exemplify one of a number of automatic arrangements which may be utilized in connection with the present invention for affording an automatic control of conditions determining the operation of the pump of the present invention.

Operation

In operation, the water will be admitted to the chamber within the central or body portion of the casing, and will thence distribute itself to the side chambers and find ingress into the motor chamber through the central apertures 33 and through the clearances afforded adjacent the rotor blades. As the blades are rotated, they will maintain a constant outward flow of water through the grooves or channels 32 and through the clearance, and thus serve to maintain a water seal or water packing to the extent, if any, required to afford a seal against the escape of air. The water thus admitted and maintained within the rotor chamber, together with water drawn in through the port 49 (or 490), will under centrifugal action, assume the form of a ring, which ring will travel at a high velocity around the circumferential wall of the rotor chamber.

When the water ring reaches the area of relative confinement afforded by the abruptly ending block-off wall 22, the water entrapped in each pocket will be driven inwardly, thus expelling the air from the base of the pocket through the discharge port 47. Immediately thereafter, the water temporarily confined

by the block-off wall 22 will suddenly be released from confinement at the knife edge 24 and will flow outwardly in more or less disturbed or agitated condition, and at this point the air or gas entering through the channel 19—20 will break through the water ring and be trapped within the pockets between the rotor blades.

By configuring the wall of the rotor chamber in the manner indicated, and by giving the block-off wall 22 a relatively abrupt inward convergence, the air will be suddenly expelled by the inthrust of the entrapped water at the point of discharge, and, coincidentally with the sudden confinement of the water at the air discharge point, the water will be suddenly released from confinement at the air inlet point, and these two actions tend to balance against one another; or, in other words, a hydraulic balance is maintained, which increases the effectiveness of the pumping action. This arrangement is more desirable than one in which the progressive confinement of the water is gradual throughout a considerable portion of the line of travel of the water ring, since in practice the quick acting block-off not only pumps more air but with less actual expenditure of power as compared with a construction having a gradual block-off.

The pumping action of the rotor tends to maintain an increased pressure in the outer chamber as compared with conditions within the rotor chamber, and this differential in pressure assists in the maintenance of a water flow through the clearance and through the grooves 32 in the rotor blades, and supplements the centrifugal action of the rotor in the maintenance of a water packing, which is effective in confining the air or gas within the pockets between the rotor blades and discharging it through the ports 47.

When, however, atmospheric air or gas is admitted through the pipe 54, the equalization of pressure conditions within the rotor chamber and within the outer chamber will cause a reduction in the quantity of water in the rotor chamber to a point below the amount required for normal operation, so that water will be expelled from the rotor chamber to the degree required to unload the pump and permit it to operate idly with a minimum expenditure of power until the admission of atmospheric air or gas is again reduced, which again increases the inflow of water to the rotor chamber to the amount required to establish pumping conditions.

The arrangement is one which is simple in construction, in that it consists of relatively few parts of arcuate construction properly designed to secure high efficiency in operation. By properly locating the water outlet port 52 (or 520) and the water inlet port 49 (or 490), and by properly restricting the dimensions of these ports with relation to

the proportions and arrangement of the rotor chamber, it will be possible to satisfactorily control the disabling and reconditioning of the pump solely by the admission of atmospheric air or gas without the employment of valves or similar automatically controlled devices for establishing the required conditions, although the employment of such devices, as indicated, for example, in Fig. 4, is contemplated, and the same may be employed where conditions require, or where the efficiency in operation will be increased.

The present invention represents a satisfactory simplified form in which the results are attained in the manner described, but it is not the intention, unless otherwise indicated in the claims, to restrict the invention to a device of the simplified form shown, since modifications thereof are contemplated and are deemed to be within the scope and principle of the present invention.

Furthermore, it will be understood that in the description, such expressions as top, bottom, and sides, are used for purposes of convenience, but that a repositioning of the device, or a re-locating of parts in positions other than those heretofore described, is within the scope of the invention.

I claim:

1. In a rotary pump of the class described, the combination of a casing providing an inner rotor chamber and an outer chamber, means for affording a discharge of liquid from the rotor chamber into the outer chamber, means for affording a duct for liquid from the lower portion of the outer chamber to the rotor chamber, a rotor within the rotor chamber adapted to draw in air or gas to the rotor chamber and expel the same therefrom through the action of the liquid associated with the rotor in the normal operation of the device, and to maintain lower pressure conditions within the rotor chamber during normal operation than in the outer chamber, and means for admitting excess of air or gas to the system to substantially equalize pressure conditions within the rotor chamber and the outer chamber, with a resultant discharge of liquid from the rotor chamber into the outer chamber to lower the liquid level in the rotor chamber below that required for effective operation, the liquid duct affording a passage for the return of liquid from the outer chamber to the rotor chamber after admission of extraneous air or gas is cut off.

2. In a rotary pump of the class described, the combination of a casing affording an inner rotor chamber and an outer chamber, a rotor journaled to rotate within the rotor chamber and having blades provided along one edge with a groove adapted to coact with the adjacent wall of the rotor chamber in the maintenance of a water packing, and the inner and outer chambers being in communication near the axis of the rotor, to provide

for the inflow of liquid to communicate with said grooves.

3. In a rotary pump of the class described, the combination of a casing affording an inner rotor chamber and an outer chamber, a rotor journalled to rotate within the rotor chamber and having arcuately extending blades curving forwardly toward the direction of rotation, provided along one edge 5 with a groove adapted to coact with the adjacent wall of the rotor chamber in the maintenance of a water packing, and the inner and outer chambers being in communication near the axis of the rotor, to provide for the inflow of liquid to communicate with said grooves.

4. In a rotary pump of the class described, the combination of a casing providing an inner rotor chamber and an outer chamber, a 10 rotor journalled within the rotor chamber, the rotor chamber having a peripheral wall located throughout a portion of its extent at a substantial distance from the periphery of the rotor, and having a block off wall throughout the remainder of its extent in close proximity to the periphery of the rotor, the block off wall merging abruptly into the more distant peripheral wall, an inlet passage communicating with the rotor chamber 15 at a point immediately beyond the opposite end of the block off wall, and an air or gas discharge port opening outwardly through the side wall of the rotor chamber at a point in proximate relation to the first mentioned 20 abrupt terminus of the block off wall.

5. In a rotary pump of the class described, the combination of a casing providing an inner rotor chamber and an outer chamber, a rotor journalled within the rotor chamber, the rotor chamber having a peripheral wall located throughout a portion of its extent at a substantial distance from the periphery of the rotor, and having a block off wall throughout the remainder of its extent in close proximity to the periphery of the rotor, the block off wall merging abruptly into the more distant peripheral wall, an inlet passage communicating with the rotor chamber 25 at a point immediately beyond the opposite end of the block off wall, and an air or gas discharge port opening outwardly through the side wall of the rotor chamber at a point in proximate relation to the first mentioned abrupt terminus of the block off wall, the air or gas discharge port and said terminus of the block off wall being both located below 30 the axis of the rotor.

6. In a rotary pump of the class described, the combination of a rotor chamber having 35 an inlet for the passage of air or gas thereto and an outlet for discharging air or gas therefrom, a container for liquid located exteriorly of the rotor chamber and having communication with the interior of the rotor chamber, a rotor within the rotor chamber, 40

adapted when liquid is maintained to an operating level to utilize said liquid in maintaining within the rotor chamber a relatively reduced pressure as compared with the pressure in the exterior liquid receptacle and in the inlet to the rotor chamber, for drawing air or gas into the rotor chamber and discharging the same therefrom, and means tending to equalize the pressure in the rotor chamber and in said liquid receptacle to reduce the liquid level in the rotor chamber below the operating level to disable the pumping action.

7. In a rotary pump of the class described, the combination of a casing providing an inner rotor chamber having an inlet for the passage of air or gas thereto and an outlet for discharging air or gas therefrom, an outer chamber and means affording communication for the passage of liquid between the chambers, a rotor within the rotor chamber adapted when liquid is maintained to an operating level to utilize said liquid in maintaining within the rotor chamber a relatively reduced pressure as compared with the pressure in the outer chamber and in the inlet to the rotor chamber for drawing air or gas into the rotor chamber and discharging the same therefrom, and means tending to equalize the pressure in the rotor chamber and in the outer chamber to reduce the liquid level in the rotor chamber below the operating level to disable the pumping action.

8. In a rotary pump of the class described, the combination of a casing providing an inner rotor chamber having an inlet for the passage of air or gas thereto and an outlet for discharging air or gas therefrom, an outer chamber and means affording communication for the passage of liquid between the chambers, a rotor within the rotor chamber adapted when liquid is maintained to an operating level to utilize said liquid in maintaining within the rotor chamber a relatively reduced pressure as compared with the pressure in the outer chamber and in the inlet to the rotor chamber for drawing air or gas into the rotor chamber and discharging the same therefrom, and means for admitting additional air or gas to the rotor chamber to more nearly equalize the pressure in the rotor chamber and the outer chamber to reduce the liquid level in the rotor chamber below the operating level to disable the pumping action.

9. In a rotary pump of the class described, the combination of a casing providing an inner rotor chamber having an inlet for the passage of air or gas thereto and an outlet for discharging air or gas therefrom, an outer chamber, and means affording communication for the passage of liquid between the chambers, a rotor within the rotor chamber, adapted when liquid is maintained to an operating level to utilize said liquid in maintaining within the rotor chamber a relative-

ly reduced pressure as compared with the pressure in the outer chamber and in the inlet to the rotor chamber for drawing air or gas into the rotor chamber and discharging the same therefrom, and means for admitting additional air or gas to the rotor chamber to more nearly equalize the pressure in the rotor chamber and the outer chamber to reduce the liquid level in the rotor chamber below the operating level to disable the pumping action, and a check valve for controlling the ingress of air or gas through the inlet to the rotor chamber.

10. In a rotary pump of the class described, the combination of a casing providing an inner rotor chamber having an inlet for the passage of air or gas thereinto and an outlet for discharging air or gas therefrom, a rotor within the rotor chamber, adapted when liquid is maintained at an operating level to utilize said liquid for passing air or gas from the rotor chamber, a chamber exterior to the rotor chamber, passages between the chambers providing inlet and outlet for liquid 20 only into and out of the rotor chamber, and means for controlling the flow through such passages and adapted in one adjustment to permit an excess of liquid to flow out of the rotor chamber to disable the pump and in 25 another adjustment adapted to permit an excess of liquid to flow into the rotor chamber to enable the pump to resume its pumping function.

In witness that I claim the foregoing I 35 have hereunto subscribed my name this 27th day of August, 1929.
